UNITED STATES PATENT OFFICE.

ARTHUR L. HALLIDAY, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 17,774, dated October 11, 1887.

Application filed September 8, 1887. Serial No. 219,120. Term of patent 3½ years.

To all whom it may concern:

Be it known that I, ARTHUR L. HALLIDAY, of New York city, in the county and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design consists, mainly, of three features or elements, a curving stem-work appearing at intervals on the face of the carpet, circular

flowers varying somewhat in size and outline and supported upon the stem-work, and a body 20 of leaf and conventionalized flower forms of irregular outline covering most of the face of the carpet between the circular flowers, and in some cases overlying or underlying those flowers. The leaf and conventionalized flower 25 forms are of a varied character, some being large double figures, others smaller and simpler in outline. Some are scroll-like in shape.

What I claim as new, and desire to secure by Letters Patent, is—

The design for carpets, consisting of the design substantially as shown.

ARTHUR L. HALLIDAY.
